Primary Examiner — Steven J Czyz(74) *Attorney, Agent, or Firm* — JoAnn M. Seaton; Griffiths & Seaton PLLC(57) **CLAIM**

The ornamental design for a retail display fixture, as shown and described.

DESCRIPTION

FIG. 1 is a perspective view of a retail display fixture, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the evenly-spaced broken lines depict portions of the article that form no part of the claimed design; the dash-dot-dash lines represent the boundary of the claimed design and form no part thereof.

1 Claim, 6 Drawing Sheets# US D961,971 S
